(57) **CLAIM**

The ornamental design for a egg yolk separator, as shown and described.

DESCRIPTION

FIG. 1 is a top perspective view of the egg yolk separator showing my new design.

FIG. 2 is a side view thereof.

FIG. 3 is another side view thereof.

FIG. 4 is another side view thereof.

FIG. 5 is another side view thereof.

FIG. 6 is top view thereof.

FIG. 7 is a bottom view thereof.

FIG. 8 is a top perspective view thereof with the top removed; and,

FIG. 9 is a top exploded perspective view thereof.

The broken lines in the drawings illustrate portions of the egg yolk separator which form no part of the claimed design.
